PROCESS AND APPARATUS FOR ATOMIZING MATERIALS FROM MOVING AIRCRAFT

Application filed March 9, 1929. Serial No. 345,856.

(GRANTED UNDER THE ACT OF MARCH 3, 1883, AS AMENDED APRIL 30, 1928; 370 O. G. 757)

This invention described herein may be manufactured and used by or for the Government for Government purposes, without the payment to us of any royalty thereon.

5 This invention relates in general to the dispersion of chemical substances and more particularly has reference to a method and apparatus for dispersing fluids from moving aircraft.

10 Previous to this time, the various apparatus and methods employed for dispersing chemical agents from moving aircraft have been for the most part of limited application to the actual tactical requirements of warfare and 15 not adaptable to certain modern requirements. The most efficient systems and devices heretofore used have been directed to the generation of smoke by the introduction of suitable materials into the exhaust manifolds of airplane motors, and the spraying of liquids in substantially the opposite direction and at an approximate equal velocity to that of the aircraft upon which they have been installed.

20 25 While a number of the expedients of this character for dispersing materials have been successful to some degree, those directed to the first mentioned type cannot readily be installed on modern aircraft, from which the exhaust manifolds have been removed to decrease the fire hazard in crashes as well as to improve the mechanical operation. In the latter variety mentioned, the object has been 30 to prevent atomization of the materials and hence, as will be apparent by reference to the description hereinafter, these are not suitable for the purposes of this invention.

In the past, it has been sought to provide 35 devices capable of dropping certain high boiling materials in large drops from considerable heights with comparatively slow planes. A toxic or vesicant fluid, such as that commonly termed "mustard gas", is usually used, with the effect of producing a highly 40 persistent blanket of material on the area over which it is dispersed.

45 It will be appreciated that it is not always desirable to contaminate ground over a considerable period and thus prevent occupancy 50 until the area is cleared. If comparatively

non-volatile material is used and dispersed in large drops, as was sought in the prior apparatus, this condition will manifestly obtain. If on the other hand it is sought to atomize the liquid so as to render it more volatile, the complicated structures which have been provided in the past are not suitable for the small and fast planes which usually are better adapted to this purpose.

55 In warfare, it is often advantageous to produce as high a number of casualties as possible among enemy troops on a specified area so that an advance may be made immediately to occupy such territory. It is obvious that the ground should be contaminated for only a short period in an instance of this character (as would also be the case where it was sought to exterminate objectionable insects or similar agricultural pests) 60 where immediate occupancy of the area is desirable. It is not always desirable moreover, that curtains of smoke be dispersed from considerable heights, as a low screen is often sufficient, if not more advantageous, and may be more economically and safely produced by 65 fast moving planes on which light apparatus is installed than by the heavy apparatus which formerly required the use of large aircraft.

70 An object of this invention is to provide a method and apparatus for atomizing fluids discharged from aircraft.

75 Another object of this invention is to provide a method and apparatus for dispersing comparatively non-volatile fluids from 80 aircraft so that they will be relatively non-persistent on the ground.

85 Still another object of this invention is to provide a method and apparatus for producing low hanging and highly obscuring smoke screens.

90 A further object of this invention is to provide a method and apparatus for dispersing irritant and vesicant materials from an airplane that will not affect the pilot or 95 contact with the plane.

95 A still further object of this invention is to provide a method and apparatus for releasing receptacles containing dangerous 100

substances from airplanes in the event of emergency.

In the drawings forming a part of this specification:

5 Figure 1 is a side elevational view of the apparatus forming the subject matter of this invention.

10 Figure 2 is a side elevational view showing the apparatus installed on an airplane.

15 Figure 3 is an end view of the closure mechanism on the discharge line.

Referring by numerals to the drawings in which the same and similar elements are designated by like symbols of reference throughout, and more particularly to Figure 1, there is shown a tank 1 adapted to act as a reservoir for the particular fluid it is desired to disperse. The shape of the apparatus and its location on an airplane, as will 20 more fully hereinafter appear, may vary for the particular purposes for which it is desired to use the same, and for installation on different types of planes.

25 If non-corrosive chemicals are employed, such as mustard gas and the like, steel or such alloys as duraluminum may be used in constructing the tank. Where corrosive agents are employed, however, such as titanium tetrachloride and stannic chloride, it is 30 deemed desirable to construct the reservoir out of commercial material, preferably of the commercial metal known as Monel.

35 A line 2 communicating with the interior of the tank is suitably secured to the bottom thereof by welding, or in any other suitable manner connected to an elbow 3 through a coupling 4. The discharge line formed of the pipes 2 and 3 is preferably made of the same material as the tank 1. It is manifest 40 that one pipe may be employed if it is found more suitable, although for installing the apparatus on different types of planes, it is deemed desirable to make up the discharge line in two sections, so that various elbows 45 forming the nozzle may be substituted to insure the discharge of the chemicals at a proper distance from the plane.

50 In order to prevent contamination by the material on the airplane and to guard against 55 injury to personnel during discharge of material in the air, the material is discharged out of the area of high turbulence set up by the airplane flying through the air. This area may be easily determined on the type 60 of plane used by any of the various expedients of determining the air flow around airplanes, now in general use.

65 It has also been found advisable to direct 70 the discharge of materials through the line to the rear and at a sufficient distance back of the vertical part of the discharge line to prevent the liquid being sucked up the outside of the discharge line, as would otherwise occur, with the resulting injury to the

plane and often the pilot, if the nozzle were pointed to the front.

A valve comprising a cap forming a closure 75 5 is mounted on the mouth of the nozzle 3. The valve is preferably of the conventional dump type and the cap 5 may have affixed thereto a crosspiece 6, as shown in Figures 1 and 3, held by a bolt or other suitable attaching means 7 fastened through the center of the cap. One end of the crosspiece 6 is pivoted on a shoulder, not shown, attached to the side of the nozzle by a bolt 8, and the other end allowed to rest in a notch formed in a shoulder 9 suitably mounted on the opposite side of the nozzle. The free end of the crosspiece is provided with an aperture 11 adapted to receive a pull cord or other suitable operating medium for connection with a convenient point in the cockpit of the airplane upon which the apparatus is installed.

80 It has been found that it is essential to vent the material in the container to insure a rapid and uniform discharge of the liquid filling. For this purpose, a vent line 12 projecting to the top of the tank 1 is encased in the discharge line formed by the pipes 2 and 3. The end of the vent line 12 terminates at the same point as the mouth of the nozzle, so that the cap 5 can act as a closure for both the discharge line and the vent line.

85 The tank 1 is provided on the top with an aperture for receiving the fluids which it is desired to disperse, provided with a conventional cap or closure 13. In addition, a plurality of lugs 14 and 15 are suitably secured on the top of the tank for attachment to a suitable carrying mechanism on an airplane.

90 It is deemed desirable, as in the illustrations shown, that the lugs be of a similar type to those usually provided on bombs, so that the tank may be instantly released from the plane if a forced landing or other contingency arises in which the presence of highly reactive substances on the plane would be hazardous to the personnel or persons on the 95 ground in proximity to a crash.

100 In practice, it is advisable from both the standpoint of safety and of convenience that the tank be loaded before it is attached to an 105 airplane. In filling the tank, a stand is preferably provided to hold the apparatus a sufficient distance above the ground or floor to protect the nozzle and the valve. A void 110 should be left in the tank after it has been 115 filled to allow for expansion of the liquid due to temperature changes, and after the required amount of the material which it is desired to use has been loaded in the container through the filling hole with the valve 120 closed, the tank is then sealed with the plug or other closure 13.

125 When mounting the tank, the airplane upon which it is desired to install the apparatus is preferably rolled into position directly 130

over the apparatus, and the tank hoisted into position and secured in place by engaging the lugs 14 and 15 into brackets provided on the airplane preferably, as previously mentioned, of the conventional bomb type to allow release of the tank if it should be found necessary. The control wire 16 is then conducted to a convenient position in the cockpit for manipulation by the pilot or other personnel.

It has been found that complete atomization of liquids is obtained when they are poured from moving aircraft, due to the counter-longitudinal motion of the air at the instant the fluid is released, thus making it possible to discharge highly persistent materials in comparatively non-persistent form on the ground. It is apparent that this makes possible entirely new tactical uses of the highly persistent chemical agents heretofore employed for contaminating areas over long periods.

It is manifest that the invention is in no wise restricted to the use of any particular substances and that while reference has been had to liquids composed essentially of a single chemical compound, it is also adapted for the dispersion of solutions, suspensions, emulsions and the like containing an active chemical ingredient.

Where it is wished to use the apparatus for laying low hanging smoke screens or for sky writing, either titanium tetrachloride or stannic chloride is most generally used, while in distributing vesicant substances where highly toxic and irritant properties are desirable, mustard gas is most usually employed. For the extermination of agricultural pests such as the boll weevil or mosquito larvae in swamps, other materials may be found which will serve more suitably for the purpose.

When it is desired to discharge the material after a proper altitude and course have been attained by the plane, and wind velocity and direction estimated, the control wire 16 is pulled, thus opening the valve at the end of nozzle 3 and setting the material free to flow out by gravity feed. In general, the most favorable position is one upwind from the target, with due allowance given for the drift of the plane. Atomization of the liquid takes place at the instant of discharge, due to the counterlongitudinal motion of the plane, as previously explained.

If titanium tetrachloride is used for producing a low hanging smoke screen or for sky writing, a very dense cloud is produced as the material is atomized, which settles and drifts with the wind. It has been found that the apparatus described above, when loaded with this material is suitable for producing smoke screens for ground uses up to an altitude of a hundred feet, spreading the smoke very rapidly from the plane to the ground.

In instances where mustard gas or other

similar persistent toxic or vesicant liquids are used, extremely large numbers of very fine drops are produced which drift with the wind and fall to the ground, and work efficiently at the same altitude. The area over which the atomized gas may be spread is of course dependent upon the size of the container employed for holding the material.

In the case of the latter materials, the extremely minute droplets of the gas or similar liquid produced by the atomization of the material on contact with the air readily evaporate after reaching the ground, so that while a large number of casualties may be obtained, the material is relatively non-persistent and an area so contaminated can quickly be occupied by other troops without harmful results.

It is manifest that the same will apply in the use of similar substances which are dispensed over fields or on swamps where it is necessary that the substances have no ill effects on persons entering the area operated upon shortly after it has been sprayed.

It will be at once apparent that this method has many advantages over that heretofore employed, where it has been essential to wait for several days and careful attention paid to the weather before an area over which mustard gas had been distributed could be occupied. In general, cool weather has often tended to prevent occupancy of sectors which have been heavily gassed for periods of several weeks.

The minute droplets afforded by the atomization process as presented by the present apparatus are so dense that they can be effectively and uniformly distributed over entire areas, depending upon the quantity of liquid dispersed, so that an object the size of a man within the specified sectors can be affected unless completely protected.

The great reduction of weight in the apparatus which has been made possible through elimination of the use of pressure with the necessary mechanical appliances, and by dispensing with any atomizing equipment which has burdened previous devices, allows the installation of this apparatus on small pursuit planes operated by a single pilot. The simplicity of operation which merely requires pulling a cord located in the cockpit and thus allowing the material free to discharge, also recommends itself over the complicated structures heretofore necessary. It is highly desirable that apparatus in which special atomizing equipment is not provided be installed on fast planes, as it has been found that the speed of the plane affects the atomization process, inasmuch as the counter motion between air and liquid is the atomizing influence.

The economy which is afforded in atomizing materials also is of marked advantage where the weight carried by a plane, and particularly small planes, is an essential factor, as by atomizing materials, far wider

areas may be contaminated than can possibly be accomplished where the substance is dropped in its normal state, as was previously done.

5 There is thus accomplished by this invention a method and apparatus for atomizing materials discharged from airplanes and in which the previous atomizing and pressure equipment heretofore used is dispensed with 10 and thus the weight materially reduced, so that installation is allowed on small pursuit planes, and an allowance for a greater area being contaminated by the reduction of weight and the increase in capacity for containing materials, and also allows for the dropping of relatively non-volatile material in comparatively non-persistent forms without injury to the airplane or personnel operating the same.

20 While we have shown and described the preferred embodiment of our invention, we wish it to be understood that we do not confine ourselves to the precise details of construction herein set forth, by way of illustration, as it is apparent that many changes and variations may be made therein, by those skilled in the art, without departing from the spirit of the invention, or exceeding the scope of the appended claims.

25 We claim:

1. An apparatus for atomizing fluids from moving aircraft comprising, means to store the fluid, a line communicating with the storage means opening at a discharge point, 35 a vent line communicating with the storage means, and common means closing the discharge line and the vent line.

2. An apparatus for atomizing fluids from moving aircraft comprising, means to store the fluids, a line communicating with the storage means opening at a discharge point, a vent line encased in the discharge line terminating at the discharge point, a closure to normally prevent discharge and venting of 45 the fluids and means to remove the closure.

3. An apparatus for dispensing fluids comprising a container for storing the fluids, a discharge line communicating with said container at a relatively low point thereof and 50 opening at a discharge point remote from the container, a vent line encased within said discharge line, having its internal end opening near the top of said container and its external end at the discharge point, and a closure to normally close both said discharge and said vent lines.

4. An apparatus for dispensing fluids comprising a fluid container, discharge and vent lines communicating with the interior of said 60 container through the same opening, both of said lines terminating at a discharge point remote from the container, and a common closure for closing both of said lines.

5. An apparatus for dispersing fluids comprising a fluid container, discharge and vent

lines communicating with the interior of said container and terminating at the same point externally of said container, and a common means for closing said lines.

In testimony whereof we affix our signatures.

NICHOLAS E. OGLESBY.
